United States Patent Office

Des. 196,470
Patented Oct. 1, 1963

196,470

DISPLAY STAND

Earnest Andrew Hendley, Doraville, Ga., assignor to Union Bag-Camp Paper Corporation, Chamble, Ga., a corporation of Virginia

Filed Dec. 28, 1962, Ser. No. 72,989

Term of patent 14 years

(Cl. D80—9)

FIG. 1 is a front perspective view taken from one end of a display stand showing my new design, the rear and opposite end being essentially the same as the front and the end shown, respectively.

I claim:

The ornamental design for a display stand, as shown and described.
